UNITED STATES PATENT OFFICE.

AXEL MAGNUSSON, OF NEW YORK, N. Y., ASSIGNEE TO OTIS ELEVATOR COMPANY, OF JERSEY CITY, NEW JERSEY, A CORPORATION OF NEW JERSEY.

SPRING-MOTOR MECHANISM AND ATTACHMENT FOR OPERATING ELEVATOR-SAFETIES.

1,034,472.

Specification of Letters Patent. Patented Aug. 6, 1912.

Application filed May 19, 1908. Serial No. 433,779.

To all whom it may concern:

Be it known that I, AXEL MAGNUSSON, a citizen of the United States, residing in the city of New York, in the county of New York and State of New York, have invented a new and useful Improvement in Spring-Motor Mechanism and Attachments for Operating Elevator-Safeties, of which the following is a specification.

10 My invention relates to that type of emergency brake for elevators in which gripping jaws carried by the elevator car are adapted to grip the vertical guide rails extending through the elevator shaft. This 15 type of brake mechanism is well known in the art and is shown, for example, in the patent to John, No. 665,225, January 1, 1901.

One of the objects of the present invention is to provide improved means for manually 20 controlling the application of the guide brakes.

Another object of the invention is to provide means for supplying power to apply the brakes in connection with both manual and 25 automatic devices for controlling the operation of said means.

Still another object of the invention is the provision of electrical means for controlling the application of the brakes.

30 Other objects will appear hereinafter, the novel combinations of elements being set forth in the appended claims.

Referring to the accompanying drawings, Figure 1 is a general view showing guide 35 brake mechanism for an elevator, and also showing diagrammatically the electrical system of control for the motor and brake mechanism; Fig. 2 is a view of the electro-magnet and means operated thereby for controlling the brake mechanism; Fig. 3 is a diagrammatic view of an elevator system to 40 which my invention may be applied; and Fig. 4 illustrates the governor mechanism for automatically effecting the operation of 45 the brakes when the speed becomes excessive.

As herein shown, the elevator car C is lifted and lowered by the motor M connected to the car through the cables 1 attached to the car C and counterweight W and passing

around the guide sheaves 2 and friction 50 drive sheave 3 on the motor shaft. The brake mechanism may be placed either above or below the elevator car, but is preferably located beneath the floor of the car, and, as here shown, is mounted on a supporting frame B comprising sides *a* and *b* secured to the under surface of the car floor. Pairs of gripping jaws 4, 5 and 4', 5' are pivoted at 6 and 7, respectively, and are adapted to grip the stationary vertical guide rails 8, 8'. The jaws are operated by cams 9 and 9' on the outer ends of short rods 10 and 10'. Between these rods and in line therewith are two more rods 11, 11' mounted in bearings 12, 12' and having their inner ends provided with right and left-hand screw threads to receive the correspondingly threaded safety drum 13. The adjacent ends of the rods 10, 11 and 10', 11' have right and left-hand threads to receive the internally 70 threaded pinions 14, 14'. These pinions are in mesh with rack bars 15, 15' connected by a yoke 16. A stem 17 extends from the yoke and is guided in a bracket 18. A coil spring 19 mounted on the stem 17 between the yoke and bracket is normally under tension and is adapted to operate the rack bars as will appear later. To a shaft 20 journaled in brackets 21 and 22 are secured the pinions 23 and 23' which are in mesh with the rack 80 bars 15 and 15'. A sprocket wheel 24 on the end of the shaft 20 is connected by a sprocket chain 25 to a pinion 26 adapted to be operated by a hand wheel 27 located in any convenient position in the car. 85

The shaft 20 is normally held against rotation by means of a trip lever 28 pivoted at 29 to the frame B. A disk 30 keyed to the shaft 20 has a recess in its periphery to receive a projection or small anti-friction roller 31 on the trip lever. The outer end of the trip lever is connected to the core 32 of an electro-magnet 33 which, when energized, holds the trip lever in operative position. A tension spring 34 may, if desired, 90 be attached to the trip lever to insure its movement to inoperative position when the magnet is deenergized. 95

The safety drum 13 is operated by the mechanism shown in Fig. 4. A governor 35, of any suitable type, is located at the top of the elevator shaft. Around the sheave 36 of the governor passes an endless rope 37 which is held taut by means of the weight 38 and sheave 39 at the bottom of the shaft. The governor rope has the usual yielding connection with the car C at 40, and passes 10 over the directing pulleys 41, 42 mounted on the lower portion of the car, and thence to the safety drum 13 around which it is wound.

The operation of the mechanism thus far 15 described is as follows: Normally the governor rope travels with the car and rotates the sheaves at the top and bottom of the well and also the centrifugal governor mechanism. When the car speed exceeds a predetermined limit the governor operates 20 the gripping device 43 to hold the governor rope stationary. As the car continues to move the governor rope will be disconnected from the car at 40 and the relative movement 25 of the rope and car will rotate the safety drum 13. The motion of the drum 13 begins substantially at the same time the governor rope is gripped and the rods 11 and 11' which are held against rotation immediately 30 commence to move out longitudinally and carry with them the gears 14, 14', the rods 10, 10' and the cams 9, 9', the latter operating to apply the gripping jaws to the guide rails. Whenever the circuit of the 35 electromagnet 33 is broken, the trip arm 28 is released from the disk 30 and permits the shaft 20 to rotate. The spring 19 will then move the rack bars inwardly and rotate the pinions 14, 14' and 23, 23'. The rotation 40 of the pinions 14 and 14' on the rods 11 and 11' moves said pinions and the rods 10 and 10' outwardly, and the rotation of the pinions on the rods 10 and 10' gives said rods an additional movement toward the gripping 45 jaws. This operation of the spring 19 to apply the brakes may be either independent of the operation of the safety drum, or both devices may operate together, as will appear hereinafter.

50 The hand wheel 27 is used to release the gripping jaws and re-set the brake mechanism after the spring 19 has operated. By turning the hand wheel in the proper direction, the pinions 23 and 23' move the rack bars outwardly and compress the spring 19 and the disk 30 is also rotated into position 55 to be held by the trip lever 28. The rack bars rotate the pinions 14 and 14' backward and withdraw the cams 9 and 9' so as to release the gripping jaws. The hand wheel may also be used either to apply the gripping 60 jaws more tightly or to ease them sufficiently to permit the car to move slowly

to a floor landing in case the brakes have brought the car to rest at an intermediate 65 position. The hand wheel may also be used at any time to effect the operation of the brakes, for by turning the wheel by hand sufficient force may readily be applied to release the trip lever 28 and permit the spring 70 19 to operate the brakes, assisted if desired by the operator at the hand wheel 27.

The present invention is especially adapted for use with electrically operated and controlled elevators, and by way of illustration I have herein shown a well known system of electrical control in connection with the present invention. This system comprises a motor armature A, a shunt field winding S, reversing switches R, R', 75 a potential switch P, and a controller switch E in the elevator car. Current is supplied from any suitable source to the positive and negative mains designated + and -, respectively, and connected through the line 80 switch L to the movable contacts 45 and 46 of the potential switch. The circuit through the potential switch magnet is as follows,—from the positive main through switch L, contacts 45 and 47, winding 49 of the potential switch magnet, conductor 50, safety switch 51 in the car, winding 52 of the electro-magnet 33, conductor 53, switch contacts 54, conductors 55 and 56, contacts 48 and 46, and thence to the negative main. 85 This circuit is normally closed and receives current to hold the potential switch closed so that current may be supplied to the motor and controlling circuits. The parts are shown in their normal position with the 90 motor at rest. If the controller lever 57 in the car be moved to the left to bridge the contacts 58 and 59, a circuit will be established as follows,—from the positive main through contacts 45, 47, conductor 60, magnet winding 61 of reversing switch R, conductor 62, contact 58, switch lever 57, contact 59, conductor 56, and thence to the negative main. The reversing switch R will now operate to close a circuit to the motor 95 armature as follows,—from the positive main through contacts 45, 47, conductors 60, 63, reversing switch contacts 64, brush 65, armature windings, brush 66, reversing switch contacts 67, and thence to the negative main. A circuit is also established through the shunt field winding 3, by way of conductor 60, through reversing switch contacts 68, 69, 70, conductors 71, 72, field winding S, and conductor 73 to the negative main. The motor armature and field winding now receive current and the motor is operated to lift the car. A reversal of the controller lever 57 effects a reversal of the motor in the well known manner.

100 Whenever the potential switch P is 105 110 115 120 125

opened either by the main line potential falling below a predetermined value or the switch magnet circuit being interrupted at any point, the current supply will be cut off from the motor, the electro-magnet 33 in said circuit will be deenergized, the trip lever 28 released, and the emergency brakes applied. These operations may be effected at any time and the car brought quickly 10 to rest by opening the safety switch 51. The usual limit switches, slack cable switch, and other safety devices may be included in the circuit of the potential switch magnet, if desired.

15 A switch lever 75 is connected at one end to the cam 9 and holds the switch 54 closed while the cam is in its inner position and the gripping jaws released. When the cam is moved outwardly, however, to operate 20 the gripping jaws, the contacts 54 are separated to open the potential switch magnet circuit. When the safety drum 13 is rotated to apply the emergency brakes, it will not only do so by direct operation of 25 the cams 9 and 9', but the initial movement of the cam 9 will separate the contacts 54 and effect the operation of the pinions 14 and 14' which will increase the power and speed with which the cams are 30 operated, while at the same time cutting off the current supply from the motor.

I wish not to be limited to the exact construction herein disclosed, as various changes in details of construction and arrangement 35 of parts might be made without departing from the spirit and scope of the invention as defined in the appended claims:

What I claim as new and desire to have 40 protected by Letters Patent of the United States is:—

1. In brake mechanism, the combination with gripping jaws, of a screw-threaded rod, a cam carried by the rod, a toothed pinion mounted on the rod, a rack meshing with 45 the pinion, and means for operating the rack.

2. The combination with gripping jaws, of screw-threaded rods, cams carried by the rods, pinions mounted on the rods, racks meshing with the pinions, a yoke connecting 50 the racks, and means for operating the racks.

3. The combination with rack bars, of a yoke connecting the rack bars, gripping devices, operating connections between the gripping devices and rack bars, automatic 55 means to operate the rack bars, and a trip device controlling said operating means.

4. The combination with a gripping device, of a rack bar, power-transmitting means between said parts, and appliances for operating the rack bar, and an electromagnetic tripping device associated with said appliances.

5. The combination of a guide rail, a de-

vice to grip said rail, a rack bar, power transmitting connections between said gripping device and said rack bar, an operating spring, a trip device for holding the spring under tension, and electro-magnetic means for operating the trip device.

6. The combination with a brake, of a device for operating the brake, a second device for effecting an additional operation of the brake, means for holding said second device inoperative, an electro-magnet for releasing said means, and a switch in the circuit of 75 said electro-magnet connected for operation to said first-named device.

7. The combination with a brake, of a plurality of separately operable devices for operating the brake, trip mechanism controlling one of said devices, electromagnetic means controlling the operation of said trip mechanism, and controlled by the operation of the other device, and manually operable means for controlling one of said devices.

8. The combination with brake mechanism, of devices for operating said mechanism, an electro-magnet, tripping mechanism operated by the electro-magnet for effecting the operation of one of said devices, and a switch in the circuit of the electro-magnet winding operated by the operation of the other of said devices.

9. In an elevator, the combination with a car, of a car brake, mechanism for operating the brake, a trip device for holding said mechanism inoperative, a potential switch, and an electro-magnet in the potential switch circuit for operating the trip device.

10. In an elevator, the combination with 100 a car, of a car brake, a safety drum, operating means therefor, operating connections between the drum and brake, additional brake-operating mechanism, and electro-mechanical means for controlling the operation 105 of said mechanism.

11. In an elevator, the combination with a car, of a car brake, a safety drum, operating means therefor, operating connections between the drum and brake, additional 110 brake-operating mechanism, a power device for operating said mechanism, a trip device for holding said mechanism inoperative, a trip holding electro-magnet, a switch in the electro-magnet circuit, and means for automatically operating the switch when the safety drum is operated.

12. In an elevator, the combination with a car, of a car brake, electrically and mechanically controlled mechanism for automatically operating the brake, and a manual device in the car for resetting said mechanism and releasing the brake.

13. In an elevator, the combination with a car, of a car brake, a motor, operating 120 mechanism between the motor and the brake,

means independent of said motor for operating the brake, and a manually operable device in the car for resetting the brake mechanism and motor.

5 14. In an elevator, the combination with a car, of a car brake, a spring motor for operating the brake, a device for holding the motor under tension, means for releasing said device and permitting the motor to 10 operate the brake, additional means for op-

erating the brake, and a manually operable device in the car for resetting the motor and releasing the brake.

In testimony whereof, I have signed my name to this specification in the presence of 15 two subscribing witnesses.

AXEL MAGNUSON.
